(57) **CLAIM**

The ornamental design for an adhesive dispenser/applicator device, as shown and described.

DESCRIPTION

FIG. 1 is a front/top perspective view of an adhesive dispenser/applicator device showing our design, the broken lines showing of the hole and the cap define the bounds of the claimed design but does not form part of the claimed design;

FIG. 2 is a left side elevational view of the design of FIG. 1, the right side is a mirror image;

FIG. 3 is a top plan view of the design of FIG. 1;

FIG. 4 is a bottom plan view of the design of FIG. 1;

FIG. 5 is a front end view of the design of FIG. 1;

FIG. 6 is a rear end view of the design of FIG. 1;

FIG. 7 is another front/top perspective view of an adhesive dispenser/applicator device showing our design, the broken lines showing of the hole and the cap define the bounds of the claimed design but does not form part of the claimed design;

FIG. 8 is a left side elevational view of the design of FIG. 7, the right side is a mirror image;

FIG. 9 is a top plan view of the design of FIG. 7;

FIG. 10 is a bottom plan view of the design of FIG. 7;

FIG. 11 is a front end view of the design of FIG. 7;

FIG. 12 is a rear end view of the design of FIG. 7;

FIG. 13 is another front/top perspective view of an adhesive dispenser/applicator device showing our design, the broken lines showing of the hole and the cap define the bounds of the claimed design but does not form part of the claimed design;

FIG. 14 is a left side elevational view of the design of FIG. 13, the right side is a mirror image;

FIG. 15 is a top plan view of the design of FIG. 13;

FIG. 16 is a bottom plan view of the design of FIG. 13;

FIG. 17 is a front end view of the design of FIG. 13; and,

FIG. 18 is a rear end view of the design of FIG. 13.
